CENTRIFUGE CONSTRUCTION WITH SEMI-AUTOMATIC CONTROLS FOR A MOBILE VACUUM CHAMBER

Edward G. Pickels, Palo Alto, Calif., assignor to Specialized Instruments Corporation, Belmont, Calif., a corporation of California

Application May 17, 1948, Serial No. 27,549

5 Claims. (Cl. 233—1)

1

This invention relates generally to centrifuge apparatus, particularly apparatus in which the centrifuge rotor is adapted to be enclosed in an evacuated chamber during its operation.

It is an object of the present invention to provide a centrifuge apparatus having novel means for moving the vacuum chamber between open and closed positions with respect to the centrifuge rotor.

Another object of the invention is to provide centrifuge apparatus of the above character in which the means for moving the vacuum chamber facilities obtaining a good vacuum tight seal between the main body of the vacuum chamber and its cooperating cover.

Another object of the invention is to provide centrifuge apparatus of the above character in which the means for moving the vacuum chamber is semi-automatic, in that movement to open or closed positions is instituted manually and controlled automatically to arrest movement when the chamber reaches normal full open or closed positions.

Another object of the invention is to provide a centrifuge of the above character having certain safety features, including protection against starting the rotor when the vacuum chamber is open, and protection against an attempt to open the chamber before breaking the vacuum within the same.

Further objects of the invention will appear from the following description in which the preferred embodiments have been set forth in detail in conjunction with the accompanying drawing.

Referring to the drawing: Figure 1 is a side elevational view in section illustrating centrifuge apparatus incorporating the present invention.

Figure 2 is a cross-sectional detail taken along the line 2—2 of Figure 1.

Figure 3 is a cross-sectional detail taken along the line 3—3 of Figure 1.

Figure 4 is a cross-sectional detail on an enlarged scale taken along the line 4—4 of Figure 1.

Figure 5 is a cross-sectional view taken along the line 5—5 of Figure 1.

Figure 6 is a circuit diagram illustrating the various circuit connections to the driving motors.

The centrifuge as illustrated in the drawings consists generally of an outer housing 10 which serves to enclose the working parts. The rotor 11 is disposed within the housing and is operatively attached to the vertical shaft 12, by the coupling 13. A plate 14 extends above the rotor, and as will be presently explained, this plate forms a cover for the vacuum chamber 16, when the latter is in operative or closed position surrounding the rotor. Above the plate 14 there is

2 an electrical driving motor 17 and adjustable ratio drive gearing 18, to turn the shaft 12 and the rotor 11 at a desired selected speed.

The vacuum chamber 16 in this instance includes the bottom plate 19 and the cylindrical shaped side walls 21. Within the chamber there is a relatively heavy annular member 22, which serves to protect the walls 21 as well as the operator and associated parts of the equipment against injury in the event of bursting of the centrifuge rotor. This feature of the centrifuge is disclosed and claimed in my co-pending application No. 27,548, now abandoned, filed simultaneously herewith, and entitled "Centrifuge Construction."

Within the member 22 it is convenient to provide a metal shell 23, which is surrounded by a metal tube 24 through which a cooling fluid can be circulated. The purpose of shell 23 is to serve as cooling means to maintain the temperature of the rotor within desired limits.

Novel elevating means is provided in connection with the vacuum chamber 16, whereby this chamber can be moved from the open position illustrated in Figure 1, to a closed position in which it surrounds the rotor 11 and is sealed with respect to the cover plate 14. The elevating means in this instance consists of three vertically disposed lift rods 26, which extend through openings 27 and 28 in plates 14 and 19. Each rod has a threaded portion 29 engaged by a nut 31. These nuts are non-rotatable with respect to the plate 19, whereby when the rods are all rotated the nuts together with plate 19 move upwardly or downwardly, depending upon the direction of rotation. One nut can be fixed to plate 19 as indicated by screw 20, leaving the other nuts free for limited self-aligning movement relative to the plate.

The lower ends of rods 26 are engaged by the thrust bearing assemblies 33, which in turn are movably retained within the sockets 34. These sockets can be short sections of metal tubing attached at their lower ends to the bottom wall of the housing. Within each socket there is a compression spring 36 which yieldably urges the associated rod 26 upwardly. When the chamber 16 is in open position these springs carry the weight of the movable parts of the vacuum chamber, plus the weight of the lift rods 26.

Fixed to the lower end of each rod 26 there is a sprocket 37, and the sprockets of all three rods are connected together by the common chain drive 38. The chain is maintained taut by means of an idler sprocket 39 which is carried by the bracket 41. The upper ends of the rods 26 are provided with enlarged heads 42, and one rod, as for example the right hand rod appearing in Figure 1, is attached to an exten-

sion shaft 43 which extends upwardly through the partition wall 44. The upper end of shaft 43 has an operative connection with a reversible electric motor 46, as through speed reducing gearing including for example motor shaft pinion 47, gear and pinion 48 and 49, and gear 51 which is attached to the upper end of shaft 43. Except when chamber 16 is fully closed, the heads 42 of the lift rods are spaced a small distance (i. e. $\frac{1}{4}$ inch) above the top plate 14 of the vacuum chamber, and for this condition the weight of the moving parts of the chamber 16, and the rods 26, is carried by the spring 36.

The motor 46 is connected to an electrical circuit which includes both manual and automatically operated switches, as will be presently explained. Switches 1, 2 and 3 of this circuit are carried by a suitable support bracket 53, and are all operatively associated with a common lever 54. One end of this lever is pivoted at 55 to a side wall of the housing, and the other end is urged downwardly by the tension spring 56. A set screw 57 forms an adjustable abutment with the upper end of the extension shaft 43, and adjustable set screws 58, 59 and 61 form operative connections with the operating members of the respective switches 1, 2 and 3. An additional control switch 4 is mounted upon the housing and is positioned to have its operating member engaged and moved by contact with the bottom plate 19 of the vacuum chamber, when the vacuum chamber reaches the lower limit of its travel.

The circuit diagram for the motor 46 is shown in Figure 6. The motor 46 is one of the reversible type having four points of connection to the same. Conductor 62 connects the current supply line L-1 to one of the terminals of motor 46, and also to one pole 64 of the three pole double throw switch 63. This switch is manually operated to one or the other of its two operating positions for the purpose of elevating or lowering the vacuum chamber. To facilitate describing the electrical connections to switch 63, the poles of this switch have been designated at 64, 65 and 66, the contacts for one side as 67, 68 and 69, and the contacts on the other side as 71, 72 and 73. Contacts 67 and 72 are connected together by conductor 74, and conductor 75 connects these contacts to another terminal of motor 46. Switch poles 65 and 66 are connected together, and are also connected by conductor 76 to another terminal of motor 46. Signal lamp 77 is connected between pole 66 and line L-1. Switch contacts 68 and 71 are connected together by conductor 78 and are connected to another terminal of motor 46 by conductor 79. Contact 69 of the switch 63 is connected by conductor 81 to one side of the control switch 1, and the other side of this control switch is connected by conductor 82 to one side of control switch 3. The other side of switch 3 is connected by conductor 83 to the current supply line L-2. The switch contact 73 is connected by conductor 84 to one side of switch 4, and the other side of this switch connects by conductor 85 to conductor 82. Switch 2 is connected in series with the energizing circuit for motor 47. This circuit also includes the manual series switch 86.

By reference to the circuit diagram of Figure 6 operation can be explained as follows: Switches 1 and 4 are the upper and lower limiting switches respectively, and are normally closed but movable to open position. The adjustment of lever 54 together with the set screw 58

is such that when the vacuum chamber has reached its normal closed position, the switch 1 is moved to open position. Likewise when the vacuum chamber is moved toward open position switch 4 closes after such movement has been initiated, and when the chamber has reached full open position switch 4 is engaged to cause it to be opened. Thus when the main reversing switch 63 is in its upper position (as viewed in Figure 6), opening of switch 1 de-energizes the motor to arrest upward movement of the vacuum chamber. When the main reversing switch is in down position, opening of the switch 4 likewise de-energizes the motor to arrest downward movement of the vacuum chamber as it reaches its lowermost position.

Opening or closing of the vacuum chamber is initiated by manual operation of the switch 63. As connected in Figure 6 its upper position represents the position to which it is moved when it is desired to elevate and close the chamber, and when moved to its lower position the chamber is caused to open. Normally switch 63 is not moved until one desires to move the vacuum chamber to another position, and therefore after a normal opening movement of the chamber, switch 63 would be left with its poles in lowermost position. It will be noted that for the condition illustrated in Figure 6, switch 2 is open, and therefore it would be impossible for the operator to supply current to the driving motor of the rotor 17.

Assuming that the operator wishes to close the chamber for carrying out a centrifuging operation, switch 63 is thrown to close upon contacts 67 to 69 inclusive, and this serves to supply current to the motor 46 whereby this motor is driven in a direction to raise or elevate the vacuum chamber. After initial upward movement switch 4 closes. As the vacuum chamber is raised by virtue of rotation of the three rods 26, the enlarged heads 42 on the upper ends of these rods remain a short distance above the plate 14, as previously explained. When the upper edge of the vacuum chamber engages the lower side of the sealing gasket provided in plate 14, continued rotation of the rods 26 causes them to move downwardly with respect to the plate 14 (but without direct engagement with the same), and this downward movement causes switch 1 to be opened, whereby the current supply from line L-2 to the motor 46 is interrupted, and the motor stopped in this position. At the same time switch 2 is closed, thus making it possible for the operator to operate the rotor driven motor 47 by closing switch 86. The slight amount of further downward movement of the rods 26 after the vacuum chamber comes to a stationary position in engagement with plate 14, is desirable because such movement is used for operation of the switch 1, and in addition it insures good sealing engagement between the top edge of the vacuum chamber and the cooperating sealing gasket carried by the plate 14, even though the top edge may not be in a plane which is exactly parallel to the plane of the plate 14, at the time of engagement with the cooperating gasket. The final downward movement of the rods 26 causes an increased spring tension against the rods, to thereby apply closing force to the chamber walls which is distributed entirely about the same. Where the heads 42 may for example be spaced from plate 14 about $\frac{1}{4}$ inch for open position of the chamber, for full closed position they may be spaced $\frac{1}{8}$ inch.

After a centrifuging operation, when it is desired to lower the vacuum chamber, air is first admitted to the vacuum chamber to break the vacuum, and then switch 63 is thrown to its lower position whereby the circuit to the motor 46 is closed and this motor driven in a reverse direction to lower the chamber. Immediately prior to lowering of the chamber the heads 42 rise to their normal positions with respect to plate 14, thus closing switch 1 and opening switch 2. In the event the operator should neglect to first break the vacuum to the vacuum chamber, before attempting to lower the vacuum chamber to open position, the vacuum chamber would be held in closed position by virtue of atmospheric pressure, and rods 26 would be moved upwardly a limited distance under the urge of the compression springs 36. Such movement (which carries heads 42 to a distance from plate 14 beyond the position which they occupy when the vacuum chamber is open) when transmitted to the lever 54 causes opening of normally closed switch 3, thus interrupting current supply to the motor 46. This indicates to the operator that the vacuum has not been broken. When the operator proceeds to properly break the vacuum in the chamber, rods 26 will again assume their normal positions to effect closing of switch 3, thus permitting the vacuum chamber to be moved toward open position as normal.

It will be evident from the foregoing that my apparatus has many features of safety, particularly in that it avoids operation of the rotor until the vacuum chamber is in full closed position, and it prevents injury to the apparatus in the event one attempts to move the vacuum chamber to open position without properly breaking the vacuum. The action of the springs 36 is utilized in effecting operation of certain of the control switches as previously described, and they aid in applying properly distributed pressure to the vacuum chamber, in urging the same toward closed sealed position. The mechanism used for raising and lowering the vacuum chamber is relatively simple and is well adapted for operation by a reversible electrical motor.

I claim:

1. In centrifuge apparatus, a centrifuge rotor, a vacuum chamber movable between closed and open positions with respect to the rotor, a cover for the vacuum chamber against which the chamber is adapted to seal when in closed position, electric motor means for moving the vacuum chamber between closed and open positions, and means for automatically deenergizing said motor means in the event the vacuum in the chamber is not broken before endeavoring to move the same to open position.

2. In centrifuge apparatus, a centrifuge rotor, a motor serving to drive the rotor, a vacuum chamber adapted to be moved between closed and open positions with respect to the rotor, motive means for moving the vacuum chamber between closed and open positions, an electrical energizing circuit for the motor which drives the rotor, means including a switch serving to control said energizing circuit, and means for causing said switch to be opened responsive to movement of the vacuum chamber from closed position.

3. In centrifuge apparatus, a rotor mounted to turn about a vertical axis, an electric motor connected to drive the rotor, an energizing circuit for said motor, a vacuum chamber for the rotor,

a cover for the vacuum chamber mounted above the rotor and serving to seal with respect to the vacuum chamber, means for raising the chamber to a position to enclose the rotor and to seal with respect to said cover and for lowering the chamber to a position to permit access to the rotor, said last means including an electric motor and an energizing circuit for the same, a switch in the energizing circuit for the rotor motor and serving to deenergize said circuit when the switch is opened, means serving to cause closure of said switch only when said chamber is in sealed relation with respect to said cover and to effect opening of the same when the chamber is moved from closed position, a switch in the energizing circuit of the motor which drives the means for raising or lowering the vacuum chamber, said last switch when opened serving to deenergize said last named motor, and means for causing automatic opening of said last named switch responsive to initial energization of said motor to lower said vacuum chamber when a condition of vacuum exists within the same.

4. In a centrifuge construction, a centrifuge rotor, a drive means for the rotor, a stationary horizontal cover plate disposed above the rotor, a vacuum chamber for the rotor and adapted to enclose the rotor in sealing relation with the cover, motive means for raising or lowering said chamber relative to the rotor and said cover plate, said last named means including a plurality of vertical threaded rods, motive means for turning said rods in unison, members serving to carry the vacuum chamber and having threaded engagement with said rods, and spring means serving to yieldably support said rods.

5. In a centrifuge construction, a centrifuge rotor, a drive means for the rotor, a stationary horizontal cover plate disposed above the rotor, a vacuum chamber for the rotor and adapted to enclose the rotor in sealing relation with the cover, motive means for raising or lowering said chamber relative to the rotor and said cover plate, said last named means including a plurality of vertical threaded rods, motive means for turning said rods in unison, and nuts serving to carry the vacuum chamber and having threaded engagement with said rods, only one of said nuts being fixed relative to the chamber and the other nuts having nonrotatable engagement with the chamber.

EDWARD G. PICKELS.
